UNITED STATES PATENT OFFICE.

LEONARD LEROY CLOSE, OF AUBURN, INDIANA, ASSIGNOR TO AUBURN FOUNDRY CORPORATION, OF AUBURN, INDIANA, A CORPORATION OF INDIANA.

STOKER.

Application filed February 5, 1925. Serial No. 7,142.

My said invention relates to a stoker and it is an object of the same to provide a power operated device of this character which shall be economical in the use of fuel and which shall prevent smoke.

Referring to the accompanying drawings which are made a part hereof and on which similar reference characters indicate similar parts,

10 Figure 1 is an end elevation of a furnace provided with the stoker of my invention,

Figure 2, a section on line 2—2 of Fig. 1,

Figure 3, a detail plan of a connecting rod shown in Figure 2, on an enlarged scale, and

15 Figure 4, a side elevation of the parts shown in Figure 3.

In the drawings reference character 10 indicates the furnace which has a front wall 11 in front of which the forward portion of 20 the furnace extends. Such forward portion comprises a supporting part 12, a hopper feed 13 and a ram 14. The hopper feed has a bottom 15 inclined toward the furnace and a vertical wall 16 at the side next to the 25 furnace wall. A feed opening is provided at the rearward end of the inclined bottom 15 underneath which is a plate 17 inclined toward the furnace.

A pusher 18 slides along the inclined plate 30 17 to force the fuel off the plate whence it falls down on the horizontal coking plate 19. The pusher 18 is so arranged as to constitute a gate closing the aperture in the feed hopper when in its forward position while 35 the rear face acts to push the fuel off the plate 17. As shown in Figure 2 the pusher when in its rearmost position remains at some distance from the end of the plate; i. e., the rearward end of the plate constitutes 40 a preliminary coking ledge where such fuel as is not pushed off onto the coking plate 19 will receive a preliminary coking action from the heat of the furnace.

The plate 17 has perforations indicated 45 at 20 to provide ventilation for the fuel on the coking ledge and the coking plate so that the gases arising from the fuel shall be thoroughly consumed. In some instances the 50 ventilating openings at 20 may be omitted according to the nature of the coal. The ram 14 is just below the vertical portion of the plate 17 and preferably has a pocket at its forward end filled with fire-clay as indi-

cated at 21. The ram runs on rollers 22 mounted in a floor piece 23 resting at its 55 front end on a ledge 24 secured to or integral with the plate 12 and having at its rear side a ledge 25 fixed to or integral with the plate 23 on which the front end of the coking plate 19 may rest.

The main grate includes a group of grate bars 26 pivotally mounted at 27 and another group of similar rocking bars 28 pivoted at 29. The bars of the first group are connected to a link 30 which at its foremost end is 60 attached to a rockarm 33 whereby the grate bars of the front section may be rocked into positions corresponding to that of grate bar 28 if desired. In practice it is seldom necessary to move the grate bars 26 since the operation of the ram will force the entire body of fuel along the coking grate and the main grate to a sufficient extent for the purposes of combustion.

The upper or front section of the main 75 grate may comprise any number of bars 26 as may be convenient for the purpose and the rear section consisting of a greater or less number of bars 28 serves to move the rear part of the fuel bed as for advancing 80 the fuel, when substantially burnt out, to the dump plate at the rear end of the furnace. The grate bars 28 are pivotally connected to a link 32 which is secured at its front end to a lever 31 by which the bars 85 may be actuated. It may be noted in this connection that fixed grate bars 34 are interposed between the rocking grate bars and that the rocking bars have their forward edges reduced in such a manner that the 90 rocking of the bars tends to lift the fuel bed and urge it forward without breaking through the same.

Operating means for the ram 14 are found 95 on the plate 12 above the pivots of the levers 31 and 33, said means comprising rockshafts 35 bearing rockarms 36 spaced from each other and connected to the rams near opposite sides of the same by means of links 37. Each of the rockshafts has at its end nearest the adjacent side of the furnace a spur gear 38 meshing with a larger spur gear 39 pivotally mounted on plate 12 and a socket 40 is secured to each of said spur gears 39. When it is desired to operate a ram, a handle 100 of convenient length is inserted in a 105

socket 40 whereupon the fireman may rock the handle to slide the ram backward or forward.

By the arrangement shown it is possible 5 to actuate either one of the two rams indicated in Figure 1 individually or they may both be operated simultaneously according to preference.

Means for operating the pushers 18 is also 10 found at the front of the furnace and said means comprises preferably an electric motor which may be arranged to drive the shaft 41 directly or may drive a belt passing over a pulley 42 on said shaft, it being understood of course that steam or water power or the like may be substituted for the electric motor if preferred.

The shaft 41 has a beveled gear meshing 15 with a beveled gear 43 on an upright shaft which in turn is connected to the driven shaft 44 by reducing gears running in oil in a casing 45. The shaft 44 carries eccentrics 46 operating on pitmen 47 connected to rockarms 48 pivoted on a rod 49. The rockarms 48 are shaped as yokes extending over the 20 ends of the pitmen 47. Rockarms 50 are also pivoted on the rod 49 and these rockarms are adjustably connected to rockarms 48 by means of set screws 51 engaging in notches arranged in a series on the upper 25 faces of the rockarms 48. Obviously this arrangement permits adjustment of the position of the pusher 18 relative to the position of its eccentric 46 and thus the starting and finishing positions of the stroke of the 30 pusher may be varied.

An arrangement is also provided whereby 35 the length of the stroke of the pushers may be varied and this comprises a set screw 52 having threaded engagement with an intermediate portion at the upper end of the yoke-shaped rockarm 50 which, as will be seen in Figure 2, has arms extending at opposite sides of those of the yoke-shaped rockarm 48 and a portion extending over the upper face of the rockarm 48 in which portion the set screw 51 is mounted. The set screw 52 may be connected as by a swivel connection to the front end of a connecting rod 53 which carries pins 54 mounted to slide in slots 55 of rockarm 50.

The connecting rod 53 is formed in two sections *a* and *b* having flattened parts overlying each other which parts are connected 45 to each other by a bolt 56 and are normally held in place by means of a coiled spring 57 bearing on the section *a* said coiled spring surrounding the bolt and bearing at its lower end on an extension 58 of the section *a* 50 mounted to slide between guides 59 on section *b*. The extension 58 is slotted at 60. This connection permits the two sections to yield in case the movement of the pusher 18 is prevented by a stone or other obstruction, 55 when the give-way or throw-out joint per-

mits the oscillating arm to continue its operation while the combined gate and pusher remains stationary until the obstruction has been removed. Transverse members 61, which may be formed as anti-friction rollers 70 are located under the extension 58 to prevent excessive friction and consequent binding, as by reason of rust or grit in the joint.

In the operation of my device the pusher 18 is moved to and fro slowly by the motor 75 driven shaft 46 which may be operated at about 4 R. P. M. Adjustment having been made for the length and position of stroke according to the nature of fuel the device may be set in operation and will permit a 80 certain amount of coal to fall on plate 17 which is forced off the plate in greater or less part and falls on the coking plate 19. Some of the coal will remain on the ledge 85 at the rear end of plate 17 and be partially coked before its passage from said plate and this operation is maintained continuously while the furnace is working. Meantime the ram 14 is operated at intervals in the discretion of the fireman to push the fuel forward off the coking grate and usually this will be done in two or more steps so that the ignited fuel is forced gradually off the coking grate pushing ahead of it the body 90 of fuel on the main grate. In many cases 95 this operation will suffice to carry the ashes and clinkers to the dump grate but if not the lower or rearmost section comprising bars 28 is operated to cover the dump grate and it may be necessary to operate the front section 100 comprising the bars 26. When the ram 14 is returned to the position shown in Figure 2 the fuel which has accumulated upon the upper face of the ram will fall on the coking grate and coking action of said fuel 105 will continue until it in turn is forced out on the main grate.

It will be obvious to those skilled in the art that various changes may be made in my device without departing from the spirit of the invention and therefore I do not limit myself to what is shown in the drawings and described in the specification but only as indicated in the appended claim.

Having thus fully described my said invention, what I claim as new and desire to secure by Letters Patent is:

The combination in a furnace having a front wall, of a stoker comprising a main grate, a coking plate at the end of said grate 115 adjacent the front wall, a floor piece supporting one end of said coking plate and extending forwardly of the furnace wall, rollers mounted in said floor piece, a ram disposed normally without the furnace and 120 slidable on said rollers for pushing fuel off the coking plate, a hopper above the coking plate, an inclined plate disposed below said hopper and extending beyond the hopper 125 and into the furnace, a pusher slidable be- 130

tween said hopper and said inclined plate for feeding charges of fuel from the hopper onto the coking plate, said inclined plate having its lower end extending downwardly 5 in close proximity to said ram and being perforated to permit ventilation, power operating means adapted to continuously reciprocate said pusher, and independent means

for manually operating said ram, substantially as set forth.

In witness whereof, I have hereunto set my hand at Auburn, Indiana, this 31st day of January, A. D. nineteen hundred and twenty-five.

LEONARD LEROY CLOSE.
